[57] CLAIM

The ornamental design for a brush for removing lint, as shown and described.

DESCRIPTION

FIG. 1 is a side elevational view of a brush for removing lint showing my new design;

FIG. 2 is an end elevational view as seen from the bottom of FIG. 1;

FIG. 3 is an elevational view of the opposite end thereof;

FIG. 4 is an exploded side elevational view thereof;

FIG. 5 is an end elevational view as seen from the top of the brush, shown without the cap; and

FIG. 6 is an end elevational view as seen from the bottom of the cap.

The undisclosed sides are the same in appearance as the sides shown.

FIG. 3

FIG. 5

FIG. 1

FIG. 4

FIG. 6
